CLAIM

The ornamental design for a pick-up unit for electronic
guitar, as shown and described.

DESCRIPTION

FIG. 1 is a perspective view of a pick-up unit for elec-
tronic guitars showing my new design;

FIG. 2 is a top plan view thereof;

FIG. 3 is a side elevational view thereof;

FIG. 4 is a front elevational view thereof;

FIG. 5 is a plan view of the underside thereof; and

FIG. 6 is a perspective view thereof.

The broken line showing of an electronic guitar is for
illustrative purposes only and forms no part of the
claimed design.
